UNITED STATES PATENT OFFICE.

LOGAN CUMMINS, OF MEMPHIS, TENNESSEE.

CUFF-HOLDER.

SPECIFICATION forming part of Letters Patent No. 651,239, dated June 5, 1900.

Application filed March 6, 1900. Serial No. 7,499. (No model.)

To all whom it may concern:

Be it known that I, LOGAN CUMMINS, a citizen of the United States and a resident of Memphis, in the county of Shelby and State 5 of Tennessee, have invented a new and Improved Cuff-Holder, of which the following is a full, clear, and exact description.

The object of the invention is to provide a new and improved cuff-holder arranged for 10 convenient attachment to a coat-sleeve at any desired point of its length to permit of bringing the cuff into the desired position relatively to the sleeve, the construction of the cuff-holder permitting easy attachment to or 15 detachment of the holder from the cuff and at the same time allowing the desired transverse movement of the cuff relatively to the sleeve.

The invention consists of novel features 20 and parts and combinations of the same, as will be fully described hereinafter and then pointed out in the claims.

A practical embodiment of the invention is represented in the accompanying drawings, 25 forming a part of this specification, in which similar characters of reference indicate corresponding parts in all the views.

Figure 1 is a side elevation of the improvement as applied and with the sleeve in section. 30 Fig. 2 is a plan view of the improvement, and Fig. 3 is a perspective view of a modified form of the improvement.

The improved cuff-holder consists, essentially, of a clasp A, adapted to engage the inner edge of a cuff B, the clasp being mounted 35 to turn at one end of a link C, having its other end connected with the frame D' of an attaching device D, adapted to be secured to the inside of the sleeve E, as is plainly illustrated in Fig. 1. The clasp A is preferably made of a single piece of spring metal to engage the cuff at opposite sides, the clasp appearing in the shape of a hook, between the members of which is forced the cuff material 40 so as to secure the clasp by frictional contact to the cuff. The end C' of the link C receives the shank A' of the spring-clasp A to form a swivel-joint, so that said end C' is free to turn on the shank A' for the purpose herein- 45 after more fully described.

The attaching device D is preferably provided with a spring having diverging spring-

arms D² and a coil D³ at the middle and secured by a pivot or rivet D⁴, inside of the casing or frame D', as is plainly shown in 55 Fig. 2. Prongs D⁵ extend outward at an angle to the side arms D², the said prongs being adapted to engage the sleeve E in a lateral direction, so as to securely fasten the attaching device to the sleeve. The prongs D⁵ extend a suitable distance inward from the outer ends D⁶ of the side arms, so that the outer ends form finger-pieces adapted to be 60 taken hold of by the fingers of the operator to press the members or side arms D² toward 65 each other for attaching the device to or detaching it from the sleeve E.

In using the device the clasp A is attached to the inner edge of the cuff B, the entire cuff-holder extending lengthwise of the cuff, 70 on the outside thereof, so that when the cuff is placed in position on the wrist and the operator takes hold of the ends D⁶ and presses the same toward each other then the cuff can be moved inward in the sleeve until it reaches 75 the desired position, when the operator releases the ends D⁶, so that the prongs D⁵ engage the lining or material of the sleeve E, and thereby securely connect the cuff-holder with the sleeve upon releasing the ends D⁶. 80

In order to remove the cuff and the device, the operator presses the ends D⁶ toward each other to disengage the prongs from the material of the sleeve, and by then pulling outward on the cuff-holder the cuff is pulled outward, and removal of the cuff from the wrist is thus accomplished.

On the frame D' are also secured limiting-stops D⁷ for limiting the outward movement of the spring-arms D², as is plainly illustrated 90 in Fig. 2. The end C⁸ of the link C has a swivel connection with the frame D', and said end C⁸ is set off by a bend or offset C⁴ from the end C², having the swivel-joint with the clasp A, as is plainly illustrated in Fig. 2, so 95 that when the device is applied as above described the link is free to turn at its ends in the clasp A and the attaching device D, and consequently will readily adjust itself to the distance between the outer face of the cuff 100 and the inside of the sleeve, and at the same time the link allows transverse movement of the cuff in the sleeve.

It is expressly understood that the distance

the cuff extends in the sleeve is regulated by the wearer fastening the attaching device D to the sleeve nearer to or farther from the outer edge of the said sleeve; but lengthwise movement of the cuff in the sleeve is prevented by the cuff-holder as soon as the latter is secured by the attaching device D to the sleeve.

In the modified form illustrated in Fig. 3 10 the clasp A and the link C are made the same as above described in reference to Fig. 1; but the attaching device D⁸ consists of a single piece of spring metal bent into U or V shape, the outer ends of the side arms being formed 15 with prongs D⁹ for engaging the material of the sleeve E, the same as the prongs D⁵ of the attaching device D, above described.

Having thus fully described my invention, I claim as new and desire to secure by Letters 20 Patent—

1. A cuff-holder, comprising a clasp for engagement with the inner edge of a cuff, an attaching device having spring-arms provided with prongs for engagement with a sleeve, 25 the extreme outer ends of the arms serving as finger-pieces by which the arms are manipulated in attaching and detaching the device, and a link connection between the said clasp and the said attaching device, substantially as shown and described.

2. A cuff-holder, comprising a spring-clasp for engagement with the inner edge of a cuff, an attaching device having diverging spring-arms provided with outwardly-extending 35 prongs for engagement with a sleeve, the spring-arms being adapted to be compressed to attach or detach the device, and a link for connecting said spring attaching device with said clasp, substantially as shown and described.

3. A cuff-holder, comprising a spring-clasp for engagement with the inner edge of a cuff, an attaching device having diverging spring-arms provided with outwardly-projecting 45 prongs for engagement with a sleeve, and a link for connecting said spring attaching device with said clasp, said clasp and said attaching device being mounted to turn on the ends of the link, substantially as shown and described.

4. A cuff-holder, provided with an attach-

ing device for securing the holder to a sleeve, said attaching device having a casing, and a spring with divergent arms, secured at its middle to said casing, the spring-arms having 55 outwardly-extending prongs, substantially as shown and described.

5. A cuff-holder, provided with an attaching device for securing the holder to a sleeve, said attaching device having a casing, and a 60 spring with divergent arms, secured at its middle to said casing, the spring-arms having outwardly-extending prongs, the extreme outer ends of the arms forming finger-pieces to be taken hold of by the operator, for compressing and releasing the spring-arms when attaching or detaching the device to or from the sleeve, substantially as shown and described.

6. A cuff-holder, provided with an attaching device for securing the holder to a sleeve, said attaching device having a casing, a spring with divergent arms, secured at its middle to said casing, the spring-arms having outwardly-extending prongs, and limiting-stops on the 70 frame to limit the outward movement of the spring-arms, substantially as shown and described.

7. A cuff-holder, comprising a spring-clasp for engagement with the inner edge of a cuff, 80 a spring attaching device having prongs for engagement with a sleeve, and a link for connecting said spring attaching device with said clasp, said clasp and said device being mounted to turn on the ends of the link, and said 85 link having an offset at or near the middle, to bring the axes of the ends parallel to each other, substantially as shown and described.

8. A cuff-holder, comprising a clasp for engagement with the inner edge of a cuff, an 90 attaching device for engagement with a sleeve, and a link with an offset and having a swivel connection with the said clasp and the said attaching device, substantially as shown and described.

In testimony whereof I have signed my name to this specification in the presence of two subscribing witnesses.

LOGAN CUMMINS.
